MEANS FOR MAKING WINDOWED CARTON
BLANKS COATED ON BOTH SIDES

John L. Emerick, Glenshaw, Pa.

Application February 21, 1938, Serial No. 191,693

1 Claim. (Cl. 91—50)

This invention relates to means to provide containers, particularly folding boxes made from boxboard which are interiorly, or interiorly and exteriorly moisture proofed or coated and provided with transparent windows to enable the purchaser to see the content of the box but will not permit handling of the same.

Numerous windowed cartons are now being used to show the content thereof, such cartons are usually produced from treated board, multiple ply paper board adhesively united, or the cartons are exteriorly coated with paraffin or similar material to protect the content from outside atmospheric moisture or to retain the atmospheric moisture within the carton, as may be required, containers for dry products such as cereals, crackers etc. would ordinarily be affected by the absorption of moisture, while bakers products having a high degree of moisture, such as cakes, doughnuts etc. must preserve the moisture to stay fresh and be salable. Uncoated cartons are often used, but in that case the goods are separately wrapped in waxed paper or other transparent material and then placed in the carton, which, of course considerably adds to the expense of the wrapper and extra labor.

These cartons have a transparent window of viscose or acetate, sold commercially under the trade names Cellophane, Sylphrap, and Protec-toid or Kodapak respectively, adhesively attached to the interior of the carton.

One of the main reasons that cartons having windows are paraffined only on the outside instead on the inside is the fact that no adhesive will readily adhere to paraffined surfaces and make a sealed joint between the board and the Cellophane. It is therefore the prime object of this invention to provide a windowed folding box which is paraffined on the inside, or inside and outside.

Another object of the invention is to produce a folding carton having a transparent window by simple and effective means to provide an uncoated marginal area around the window opening of the carton, so that adhesive material may be readily applied thereto to effectively provide a seal between the Cellophane and the carton.

Still another object of the invention is to provide a folding paper carton that is paraffined on both sides of the stock to insure double moisture proofing and having a window of transparent material to provide visibility of the content.

Yet another object of the invention is to provide a simple means and apparatus for producing an uncoated marginal area around the window

opening when paraffining the folding paper carton, so that adhesive compound may be readily applied to effect a seal between the Cellophane and the card board.

It is also an object of the invention to produce a windowed folding paper carton, the inside of which being coated or impregnated with a proper substance to provide a moisture proof interior, thereby preventing damaging odors of the carton to effect the content of the container.

A further object of the invention is to provide a pair of rotatably supported cylindrical coating rollers, one of which being provided with a cut-out portion for facilitating an uncoated area around the window opening of the carton and automatic synchronized means to restore, at predetermined intervals the periphery of the cut-out portion of said roller to its normal cylindrical contour.

Another object of the invention is to produce a device for coating windowed cartons embodying a pair of opposed and rotatably supported cylindrical coating rollers, one of which being adapted to completely coat the surface of the outside of a carton blank and one adapted to produce an uncoated area around the window opening on the inside of the carton-blank.

Still another object of the invention is to provide a device of the character set forth which will at all times control the level of the coating material in the portion of the coating receptacle in which the coating delivery rolls are immersed.

With these and other objects in view, the invention consists of the construction and arrangement of parts hereinafter fully described, illustrated in the accompanying drawings, and particularly pointed out in the claim hereto appended, it being understood that changes in the form, proportion and minor details of construction within the scope of the claim may be made without departing from the spirit of sacrificing any of the advantages of the invention.

Like numerals of reference designate corresponding parts in all figures of the drawings.

In the drawings:

Figure 1 is a diagrammatic view of the device for applying coating material to both sides of a windowed folding paper carton blank built in accordance with this invention.

Figure 2 is a sectional view along line 2—2 in Figure 3 of one of the coating material dispensers as used in the invention.

Figure 3 is a top view of the coating material dispenser shown in Figure 1.

Figure 4 is a plan view of an unfolded paper carton blank indicating the uncoated marginal border around the window opening.

Figure 5 shows a carton blank between a pair of opposed and co-acting coating rollers, the bottom roller being of the plain cylindrical type as shown in outline, with major portions broken away, the top roller being of the mutilated cylindrical type, shown in cross-section, and illustrating the mechanism within the roller which alternately moves the sector-plate in and out of peripheral alignment, with the coating roller in this illustration, the window opening of the carton blank being shown in central alignment with the sector plate.

Figure 6 is a view similar to Figure 5, showing the relative position of the window opening of the carton blank and the sector-plate of the mutilated coating roller, the latter being advanced for a distance of ninety degrees and the sector-plate and its associated members having assumed positions as shown.

Figure 7 is an elevational assembly view, part in section and part in outline, of the coating roller which produces an uncoated area for applying adhesive material around the edge of the window opening of a carton blank to attach thereto a transparent sheet material. The sector plate being eliminated, to disclose the mechanism which reciprocates the same.

Referring to the drawings, the numeral 10 indicates a windowed carton blank of suitable material, fed through a pair of cylindrical coating rollers 11 and 38 over belted endless conveyors 13 and 14.

Coating roller 11 is of the plain type and comprises a cylindrical hollow body 15 exteriorly covered with a layer of felted fibrous material 16. This body 15 is mounted in any suitable manner on a shaft 17 that is journaled in bearings 18 and 19 of a frame (not shown). This shaft may be continuous and extends horizontally through the coating roller, as shown in Figure 7.

Moisture proofing material, such as for instance molten paraffin, is applied to both sides of the carton blank 10 by means of the coating rollers 11 and 38 which receive the paraffin from the auxiliary rollers 22 and 23, the lowermost portions of which extend into the tray-like forward end 24 (24^a) of a receptacle 25 (25^a) respectively containing the paraffin, as shown in Figure 1 of the drawings. These receptacles 25 (25^a) will be described later.

Referring now to Figures 5, 6 and 7 in which the preferred embodiment of a mutilated coating roller 38 is illustrated, the latter is shown in three sections, the end sections 39 and 40 and the mutilated middle section 41 and drawn together by suitable distance-rods or bolts 42 and nuts 43. In this case, the end sections 39 and 40 have end-plates 44 and 45 respectively, each of which is provided with a hollow stub-shaft 46, 47. These stub-shafts consist of an enlarged and externally threaded portion 48, adapted to be inserted through the central aperture 49 provided therefore in the end-plates 44 and 45 and securely held in position by nuts 50, as shown in Figure 7. The outer end of said stub-shaft 46 is rotatably supported in a split bearing 51 of an upright bracket 52 of a bedplate (not shown). Similarly, the stub-shaft 47 is rotatably supported in a split bearing 54 of an upright bracket 55 of the bedplate, but in addition, is provided with an extension 56 to which is keyed or otherwise secured a

belt or chain wheel 57 by means of which the required motion is given to the coating roller 38.

Within the hollow stub-shafts 46 and 47 and extending through roller 38 is a centrally disposed stationary shaft 58, both ends of which being rigidly supported in suitable outboard extension brackets 59 and 60 and prevented from rotating by set-screws 61 or otherwise.

Before continuing further with the detailed description of the invention, the following should be noted:

As previously stated, the invention is principally concerned with moisture proofing (paraffin or other similar material) the interior, or interior and exterior surface of windowed folding cartons and providing an uncoated border around the edges of the window opening and thus make it possible to successfully apply a transparent cellulose tissue window made from viscose or acetate, such as for instance sold as "Cellophane" to a moisture proofed surface. At present, no adhesive is known to make these tissues adhere to a paraffin coated surface and this is one of the paramount reasons that windowed cartons are at present always only exteriorly paraffined, instead of where it should be, interiorly. This is especially true, for instance, in cake cartons, such as extensively used by bakers to hold cakes, doughnuts, or other similar bakers' products. Extensive tests have shown, that cartons interiorly naked or uncoated have a tendency to absorb the moisture from the packaged goods, thereby defeating one of the main objects of the carton that is, to retain the content moist and fresh for a considerable length of time.

If for economic reasons it is required to reduce the cost of the carton and only one side of the carton is paraffin coated, the coating should be applied to the inner surface, although a paraffin coat on both surfaces of the carton would provide a maximum of moisture proofness and at the same time considerably add to the outside appearance of the carton by giving it a high gloss and thereby improving the printed matter on the same.

Continuing with the description of the invention, 62 indicates in general the sector-like plunger, the exterior of which conforms to the peripheral curvature of the cylindrical roller 38. This plunger 62 comprises a substantially rectangular sector-plate 63 having interiorly disposed bosses 64, each provided with an aperture 65 in which a guide rod 66 is slidably inserted. These guide-rods 66 have a threaded end 67 which engages the threaded aperture 68 of suitable bosses 69 provided and arranged within the interior of roller 38, as shown (Figures 6 to 8). A locknut 70 prevents the guide rods from unscrewing.

The movement of the sector-like plunger 62 may be checked by collars 71, each held in the desired position by a set-screw 72.

To normally retain said plunger 62 in a "down" position as shown in Figure 7, a pair of expansion coil-springs 73 are provided, one end of which being fixed to the underside of plunger 62 and the other end of which being secured to the inner wall of roller 38.

Extending inwardly of said sector-plunger 62 is an upwardly convex cam 74 supported on a block 75 to which the latter is bolted, or riveted, or, if desired the said sector-plate 63, cam 74 and block 75 may be cast integral, as shown.

Of course, the size and shape of said sector-plate 63 and the peripheral opening 76 of coating roller 38 depends entirely on the size and shape

of the window opening 36 of the carton. The said peripheral opening 76 of coating roller 38, in which the edges 77 of said sector-plate 63 fits, corresponds substantially to the window opening 36 of carton 10 including the width of the uncoated area around said window opening 36.

Sector-plunger 62, mounted within roller 38, receives its reciprocating movement by means of a cam-roller 78 rotatably supported in brackets 10 79 having a common integral hub 80 that is provided with a bore 81 adapted to be received by stationary shaft 58 and securely held thereon by set-screws 82, or otherwise.

Figures 5 and 6 illustrate two positions of the 15 coating rollers 11 and 38 with respect to the window opening 36 of the carton blank 10, while Figure 1 shows a diagrammatic arrangement of the device for applying coating material to both 20 sides of a windowed carton blank 10 including the auxiliary rollers 22 and 23, each of which transfers the coating material from receptacles 25 and 25a containing said coating material to the 25 coating rollers 11 and 38 respectively.

It should be noted, that in this embodiment, 25 the circumference of the coating roller 38 corresponds to approximately the length, or if so desired to the width of the carton blank 10, it may also be possible to increase proportionally the diameter of said roller to take care of two or more 30 blanks, or if found advantageous, two or more blanks may be fed side by side through the coating rollers 11 and 38. Naturally, in either case, the window opening 36 of carton blank 10 must register with the opening 76 of the coating roller 38 and the speed of the endless conveyor that feeds the carton blanks to the coating rollers must be adjusted in timed relation with the 35 peripheral speed of the coating rollers 11 and 38.

The plain coating roller 11 may be of any desired 40 diameter and movement of the same may be transmitted by a gear or chain connection in conjunction with the power operated mutilated coating roller 38, or otherwise.

In order to apply paraffin or a similar substance 45 to both surfaces of a carton 10, the paraffin is transferred from receptacles 25-25a containing the molten paraffin by means of the auxiliary rollers 22-23, the lowermost portions thereof extending into tray-like forward ends 50 24-24a of receptacles 25-25a.

Referring now to Figures 1, 2 and 3, the said 55 receptacles comprise a rectangular reservoir 83 having a front wall 84, side walls 85, 86 and a bottom 87, the latter of which being frontwardly extended to form a tray-like extension 88. Front wall 84 does not reach the bottom 87, but instead, leaves an elongated gap 89, as best shown in Figure 2. The lowermost edge 90 of said front wall 84 is provided with one or more cut-outs 91. 60 Embedded in said bottom 87 is an electric heating element 92 which connects to a source of electric energy by means of a service chord 93 and plug 94. To keep the dirt out of the reservoir 83 I provide a cover 95.

65 To use the above described receptacle 25-25a, it is assumed that the reservoir 83 is filled with pieces of paraffin or similar material and plug 94 is connected to the source of electric energy. In a short time the paraffin will melt into a 70 water-like substance and freely flow from the reservoir 83 through gap 89 into the tray-like extension 88 until the level of the liquid paraffin reaches the apex 96 of the cut-outs 91. In that stage, no more liquid paraffin can enter the tray-like extension 88 until some of the liquid has

been gradually taken away by the auxiliary rollers 22-23, transferred to the coating rollers 11 and 38 and then to the surfaces of the carton 10.

By this method, the liquid paraffin is constantly 5 fed from the reservoir 83 to the tray-like extension 88, thus establishing a predetermined permanent level of the molten solution which entirely eliminates adjustment of rollers 22-23, to gradually lower the latter as the content of 10 the receptacle is consumed, or to raise same when renewing or adding paraffin.

Another important advantage of this means of dispensing molten paraffin is that only a small amount of the solution contacts with the auxiliary rollers 22-23, thereby eliminating so-called 15 scraping elements which usually wipe off the excessive paraffin.

The foregoing description includes the mechanism required to make certain provisions for 20 applying cellulose (Cellophane) windows to a paraffin coated surface and, at the same time, it is to be understood that the herewith described invention is not concerned with the mechanism for applying a transparent window to a carton 25 blank nor is it concerned how the carton blanks are fed to the coating rollers 11 and 38 in timed relation.

The operation of the preferred form of the invention is as follows:

30 Carton blanks 10 are placed by suitable means on endless conveyor 13 which carries the same to and between the plain coating roller 11 and the mutilated coating roller 38, each of which receives the required amount of paraffin or similar 35 material from an auxiliary roller 22 and 23 respectively. Each of these rollers 22-23 is rotatably immersed into the tray-like extension 88 of receptacle 25-25a which holds a certain quantity of hot molten paraffin at a uniform 40 level at all times. These rollers 22-23 are in frictional contact with said coating rollers 11-38 thereby transferring paraffin to the latter which in turn transfer the paraffin to both 45 surfaces of the carton blank.

As previously stated, it is one of the main 50 objects of this invention to paraffin the interior, or the interior and the exterior of a windowed folding carton. In the first case, only one of the paraffin receptacles would be required, that is for 55 the mutilated coating roller 38, roller 11 would, in that case merely serve as a squeezing roller.

As the carton blanks pass between the coating rollers 11 and 38 it will be observed that the speed of the endless feeding conveyor 13 must 55 be in synchronism with the peripheral speed of the coating roller 38 so that the opening 76 in roller 38 always registers with the window opening 36 of the carton blank 10.

Experiments have shown, that, when using a 60 plain mutilated coating roller, in which the opening 76 corresponds to the window opening 36 plus the uncoated border strip 37 of the carton blank, the paraffin coating on the exterior surface of the carton, especially around and opposite 65 said uncoated strip of the interior surface will not be coated properly, due to the unsupported portion of the carton which constitutes the uncoated area to which the transparent window material (Cellophane) is adhesively attached 70 and thus be closed against the passage of air or moisture, while nevertheless, because of the transparent character of the Cellophane it still permits visual observance of the product enclosed 75 within the carton.

Figures 5 to 7 show the interior mechanism of the mutilated coating roller 38, including the sector-plate 63 and cam 74, forming the plunger 62 which is mounted for intermittent reciprocating motion. At every revolution of the mutilated coating roller 38 the cam roller 78 contacts and rolls along cam 74 thereby raising and retaining the plunger 62 in a position in which the periphery of the sector-plate 63 conforms to the cylindrical exterior surface of roller 38, as shown in Figure 5 until the cam 74 again leaves cam-roller 78 which in turn causes the spring-tensioned plunger 62 to assume a position as shown in Figure 6. In that condition, the outer surface of sector-plate 63 assumes a position below the peripheral surface of roller 38.

Obviously, in operation, the sector-plate 63 must be retained in a position as shown in Figure 5 until the window opening 36 of carton blank 10 has passed the line of frictional contact of rollers 11 and 38 and this is readily accomplished by making the circumferential length of the upwardly convexed cam 74 in proportion to the circumferential length of the sector-plate 63.

The described mechanism, which provides uncoated marginal borders around the window opening of a windowed carton coated interiorly and exteriorly with paraffin or similar material, is of great advantage for the reason that it not only provides an uncoated marginal border around the window opening to which the Cellophane window is adhesively attached, but it also distributes uniformly the paraffin on both surfaces of the carton.

After the carton blanks have passed rollers 11 and 38 the same may be transferred by endless conveyor 14 to a suitable cooling zone and thence to a device which places and cements the transparent windows to the carton blank after which the latter is transferred by suitable means to a place for storing or packing.

From the foregoing description, it will be apparent that I have devised a very efficient method and means to produce windowed folding cartons which are moisture proofed interiorly and exteriorly and at the same time make it possible to adhesively seal the window material, such as for instance Cellophane, to the carton, thereby preserving cakes, doughnuts or other bakers products considerably longer since the moisture of the products cannot be absorbed by the interiorly uncoated carton, as is the case at present.

I claim:

In a device for applying coating to a carton blank formed with a window opening, a pair of rollers between which a carton blank is adapted to pass one roller being of the plain type, the other roller having a peripheral opening of larger dimensions than the window opening of the blank, an absorbent pad about the second roller formed with an opening registering with the opening in the roller, a shaft extending through the padded roller and about which the padded roller turns, a plunger in the padded roller shiftable radially thereof into and out of an extended position to fill the registering openings and dispose its outer face flush with the pad, rods mounted in said padded roller and engaged in sockets formed in said plunger to slidably mount the plunger, springs mounted in the roller and connected with the plunger for exerting inward pull and shifting the plunger inwardly, collars upon said rods shiftable longitudinally thereon to adjusted positions for limiting inward movement of the plunger, and an arm fixed upon said shaft and projecting radially therefrom for engaging the plunger and temporarily shifting the plunger outwardly to its extended position during rotation of the roller about the shaft.

JOHN L. EMERICK. 40
